UNITED STATES PATENT OFFICE.

OSWALD H. HANSEN, OF PORT WASHINGTON, WISCONSIN, ASSIGNOR TO HANSEN
CANNING MACHINERY CORPORATION, OF PORT WASHINGTON, WISCONSIN, A COR-
PORATION OF WISCONSIN.

CAN-FILLING MACHINE.

Application filed November 23, 1922. Serial No. 602,728.

This invention relates in general to improvements in the art of manufacturing and operating mechanisms for measuring and delivering batches of substance in rapid succession, and relates more specifically to improvements in the construction of filling machines for automatically and rapidly delivering to successive cans of a series, accurately measured quantities of material such as a mixture of liquid and peas, beans, berries or the like.

An object of the invention is to provide a can filling machine which is simple and compact in construction and efficient in operation. Another object of the invention is to provide mechanism for automatically delivering to successive cans of a series travelling at a high rate of speed, accurately measured batches of material. A further object of the invention is to provide a can filling machine having conveniently interchangeable measuring pockets and other elements, providing for conversion of the filler from one condition of operation into another. Still another object of the invention is to provide numerous improved features applicable to various types of receptacle filling machines in order to improve the general efficiency thereof. A further object of the invention is to provide can filling mechanism capable of effectively performing its function without wasting or degrading the material. Another object of the invention is to provide a machine which may be readily cleaned and maintained in sanitary condition, and the essential elements of which are readily accessible, removable and manipulable. Still another object of the invention is to provide for convenient adjustment of the proportions of the materials in a mixture delivered by a filler, and to further provide for convenient and flexible control of filling machines and the like. These and other objects and advantages of the present invention will be apparent in the course of the following description.

Some of the novel features of can filler construction disclosed but not specifically claimed herein form the subject of copending applications for Letters Patent, including Serial No. 214,205 filed January 28, 1918, Serial No. 343,698 filed December 10, 1919, Serial No. 430,131 filed December 13, 1920, and Serial No. 435,835 filed January 8, 1921.

While the present description employs relatively specific descriptive terms, such specific description should not be construed as a limitation of the scope of the present invention. Although the machine illustrated herein is especially adapted to fill open topped sanitary tin cans, the term "can" should be construed as designating any type or form of receptacle. The term "filling" is not intended to designate complete filling only but also designates a partial filling of the receptacles. The machine described may be operated with both granular material and a liquid, or with either of these substances alone. The features of the present invention are applicable to various types of machines for automatically feeding measured quantities of substances to successive receptacles of a series.

A clear conception of an embodiment of the present invention and of the operation of devices constructed in accordance therewith, may be had by referring to the drawings accompanying and forming a part of this specification in which like reference characters designate the same or similar parts in the various views.

Fig. 1 is a central vertical section through an improved interchangeable automatic can filling machine.

Fig. 2 is a transverse horizontal section through the improved interchangeable automatic can filling machine, the section being taken along the horizontal plane represented by the line II-II of Fig. 1.

Fig. 3 is a fragmentary central vertical section through the mixture measuring pockets of the improved interchangeable automatic can filling machine, showing a second form of measuring element inserted in the machine.

Fig. 4 is a fragmentary central vertical section through the mixture measuring pockets of the improved interchangeable automatic can filling machine, showing a third form of measuring element inserted in the machine.

The improved can filling machine comprises in general a main frame, granular material supply and measuring means, liquid supply and control means, means for accurately measuring successive batches of mixture of granular material and liquid, means for delivering successive cans to the ma-

chine, mechanism for automatically delivering measured quantities of mixture to the successive cans 19 as they are transported through the machine, means for automatically delivering the filled cans from the machine, and suitable power and control means for operating the various mechanisms forming the completed machine.

The main frame of the interchangeable automatic can filling machine comprises a pair of laterally spaced vertical side frames 17 which are interconnected at their upper portions by means of a stationary horizontal cross frame 13, at their intermediate portions by means of a stationary horizontal cross frame 18, and at their lower portions by means of another horizontal cross frame. The upper extremities of the side frames 17 form a support for the liquid supply tank 28 which is supported rearwardly of the machine and is provided with brine or other liquid supply and discharge pipes 26, 29 respectively. The upper portion of the side frames 17 also provides a support for the stationary vertical adjustable top plate 6 which forms a carrier for the pea or other granular material supply hopper 5. Located directly beneath the stationary top plate 6 is an annular series of seven granular material measuring pockets which is rotatable about the central vertical axis of the machine and the successive pockets of which are successively communicable directly with the hopper 5 through an opening in the top plate 6. The granular material measuring pockets are formed in telescopic upper and lower members 7, 8 respectively, which may be relatively vertically adjusted in order to vary the volumes of the successive batches of granular material measured therein. The lower member 8 is slidable in direct engagement with a stationary cut-off plate 9 which rests directly upon a circular rotary upper mixture measuring element 10 and is provided with an opening for establishing direct communication between the granular material measuring pockets and the mixture measuring pockets 30. The lower measuring member 8 may be drivingly direct connected 50 with the upper mixture measuring element 10 by means of one or more drive pins 31. The upper mixture measuring element 10 rests directly upon one of a number of interchangeable circular rotary intermediate mixture measuring elements 2, 3, 4, these coacting elements being drivingly connected by means of one or more motion transmitting pins 32. The intermediate mixture measuring element 2, 3, 4 rests directly upon a lower circular rotary mixture measuring element 11, these coacting elements being drivingly connected by means of one or more motion transmitting pins 33. The superposed and interconnected mixture measuring elements 60 are provided with vertically aligned openings

forming an annular series of seven mixture measuring pockets 30 of equal fixed capacities depending upon the particular intermediate measuring element 2, 3, 4 which is employed.

The lower rotary mixture measuring element 11 is rotatably supported upon a stationary cut-off plate 12 which is supported directly by the stationary upper cross frame 13. The cut-off plate 12 is circular in form and is provided with liquid admission openings 38 communicating with a manifold 37 which in turn communicates with the liquid supply tank 28 through a control valve 36 and the pipe 29. The cut-off plate 12 is also provided with a final discharge opening 35 for delivering measured quantities of mixture directly from the successive measuring pockets 30 to the successive cans 19 through the successive delivery chutes 14. The annular series of delivery chutes 14 is supported directly by a rotary carrier 15 which embraces the vertical main shaft 21 and is rotatable with this shaft. The successive cans 19 are urged along a horizontal can supporting surface formed upon the stationary intermediate cross frame 18, by means of interchangeable can hooks 16, each machine preferably being provided with several sets of can hooks 16 and with several guides cooperable with the can hooks in order to accommodate cans 19 of various standard sizes. The mechanism for delivering the successive cans 19 to and from the machine, and the guides which cooperate with the can hooks 16, are clearly shown and described in Patent No. 1,460,198, granted June 26, 1923.

The vertical main shaft 21 is rotatably mounted in bearings supported by the cross frames 13, 18 and has its upper end detachably drivingly connected with the lower mixture measuring element 11 by means of a removable driving head 34. The lower portion of the shaft 21 has a bevel gear 20 secured thereto, the gear 20 being drivingly connected with the can hooks 16 and with the chute carrier 15 by means of a plurality of vertical drive rods 40 as shown in Fig. 1. The horizontal main power shaft 23 is mounted in bearings supported by the cross frame 18 and one of the side frames 17, and has a bevel pinion 22 attached to an end thereof and meshing with the bevel gear 20. A driving pulley 24 carried by the power shaft 23 is drivingly connectable with the shaft 23 by means of a jaw clutch 27 which is manipulable automatically by means of safety stop mechanism, and manually by means of a hand lever 25 which also functions to control a valve in the pipe 26, as shown and described in copending application Serial No. 435,835 filed January 8, 7921.

During normal operation of the filler and assuming the product handled to be peas and

brine, and the cans 19 to be of size corresponding to the volumes of the pockets 30 with the intermediate element 2 in place as shown in Figs. 1 and 2, the various mechanisms are placed in motion by manipulation of the control lever 25. When the lever 25 is thrown toward the left as viewed in Fig. 1, the jaw clutch 27 is thrown into operative position and the flow control valve in the pipe 26 is simultaneously opened, whereupon the horizontal power shaft 23, pinion 22, gear 20 and vertical main shaft 21 are rotated and brine is automatically admitted to the supply tank 28 until the ordinary float control in the tank 28 prevents further admission of brine. The rotating shaft 21 and gear 20 transmit their motion to the can hooks 16, chutes 14, mixture measuring pockets 30 and pea measuring members 7, 8. The can hooks 16 transport the successive cans 19 beneath the chutes 14. The peas are automatically delivered from the supply hopper 5 through the top plate 6 to the successive measuring pockets in the members 7, 8 from which the measured quantities or batches of peas are delivered through the cut-off plate 9 to the successive mixture measuring pockets 30. After the successive measured batches of peas have been deposited in the successive pockets 30, brine is automatically admitted to the pockets 30 from the manifold 37 through the opening 38, the brine thus admitted being under pressure and percolating upwardly through the voids in the peas thereby filling the pockets 30 with measured quantities of mixture of peas and brine. When the filled measuring pockets 30 advance to a position above the final discharge opening 35 in the lower cut-off plate 12, the measured batches of mixture are delivered by gravity through the chutes 14 to the successive cans 19 located below the chutes. The cans thus filled are automatically delivered from the machine in the usual manner and are subsequently capped and otherwise treated to complete the packing operation. It will thus be noted that the machine automatically and rapidly delivers to each of the successive cans 19 of a series, accurately measured quantities of mixture of peas and brine.

The proportion of peas and brine comprising each batch of mixture may be readily varied by merely adjusting the volume of the pea measuring pockets such adjustment being effected by shifting the upper member 7 vertically relatively to the lower member 8, as shown and described in Patent No. 1,460,198, granted June 26, 1923. As the volumes of the chambers 30 for a given size of intermediate element 2, 3, 4, are fixed, variation of the measured quantities of peas will naturally proportionately vary the quantities of brine in the final measured batches of mixture. If it is desired to fill cans 19 of a

different standard size, it is necessary only to substitute an intermediate element 3, 4 corresponding to the size of the cans which it is desired to fill, and to provide a set of can hooks 16 and cooperating guide capable of properly coating with the selected size of cans 19. As the various elements of the machine which are adapted to be interchanged, are freely vertically removable and conveniently insertible, the change in condition of operation of the machine may be readily effected in a short period of time. As each machine is provided with several sets of interchangeable measuring elements 2, 3, 4, can hooks 16, and can guides, cans 19 of any desired capacity within the range of the interchangeable elements provided may be filled at will.

From the foregoing description it will be obvious that the mechanism is capable of automatically delivering to successive cans 19 of a series travelling at a high rate of speed, accurately measured batches of mixture of peas and brine. The machine is adapted for convenient conversion for operation in filling cans 19 of different standard sizes. The apparatus functions effectively without wasting or degrading material and the various elements of the mechanism are readily accessible, removable and manipulable. The proportions of the mixture may be accurately and conveniently adjusted and the entire operation and control of the machine may be effected by a single operator.

It should be understood that it is not desired to limit the invention to the exact details of construction and of operation of the mechanism herein shown and described, for various modifications within the scope of the claims may occur to persons skilled in the art.

It is claimed and desired to secure by Letters Patent:

1. In a can filling machine, an upper measuring element having openings therein, a lower measuring element having openings therein in alignment with said upper element openings, a removable intermediate element having openings therein of fixed size alinable with said upper and lower element openings to form measuring pockets, said intermediate element being replaceable by other intermediate elements having differently sized openings therein, means for feeding material to said pockets through said upper element openings, and means for affecting delivery of said material from said pockets through said lower element openings.

2. In a can filling machine, an upper measuring element having an annular series of openings therein, a lower measuring element having an annular series of openings therein in alignment with said upper element openings, a removable intermediate element

having an annular series of openings therein of fixed size alinable with said upper and lower element openings to form measuring pockets, said intermediate element being replaceable by other intermediate elements having annular series of differently sized openings therein, means for feeding material through said upper element openings, and means for effecting delivery of said material from said lower element openings.

3. In a can filling machine, an upper measuring element having openings therein and also having a lower surface extending transversely of said openings, a lower measuring element having openings therein in alinement with said upper element openings and also having an upper surface extending transversely of said openings, a removable intermediate element having openings therein of fixed size alinable with said upper and lower element openings to form measuring pockets and also having top and bottom surfaces cooperable with said upper and lower element surfaces, said intermediate element being replaceable by other intermediate elements having differently sized openings and top and bottom surfaces, means for feeding material to said pockets through said upper element openings, and means for effecting delivery of said material from said pockets through said lower element openings.

4. In a can filling machine, an upper measuring element having openings therein, a lower measuring element having openings therein in alinement with said upper element openings, a removable intermediate element having openings therein of fixed size alinable with said upper and lower element openings to form measuring pockets, said intermediate element being replaceable by other intermediate elements having differently sized openings therein, means for feeding granular material to said pockets through said upper element openings, means for feeding liquid to said pockets through said lower element openings, and means for effecting discharge of mixed granular material and liquid from said pockets through said lower element openings.

5. In a can filling machine, an upper measuring element having openings therein, a lower measuring element having openings therein in alinement with said upper element openings, a removable intermediate element having openings therein of fixed size alinable with said upper and lower element openings to form measuring pockets, said intermediate element being replaceable by other intermediate elements having differently sized openings therein, means for transmitting positive rotary motion from said lower element to said upper element through a cooperating intermediate element, means for feeding material to said pockets during rotation thereof, and means for ef-

fecting delivery of said material from said pockets through said lower element openings.

6. In a can filling machine, an upper measuring element having an annular series of openings therein, a lower measuring element having an annular series of openings therein in alinement with said upper element openings, a removable intermediate element having an annular series of openings therein of fixed size alinable with said upper and lower element openings to form measuring pockets, said intermediate element being replaceable by other intermediate elements having annular series of differently sized openings therein, means for transmitting positive rotary motion about the axis of annularity of said openings from said lower element to said upper element through a cooperating intermediate element, means for feeding material to said pockets through said upper and lower element openings, and means for effecting delivery of said materials from said pockets through said lower element openings.

7. In a can filling machine, stationary frame structure, an upper measuring element rotatably engaging said structure and having openings therein, a lower measuring element rotatably engaging said structure and having openings therein in alinement with said upper element openings, a removable intermediate element having openings therein of fixed size alinable with said upper and lower element openings to form measuring pockets said intermediate element being replaceable by other intermediate elements having differently sized openings therein, and means associated with said frame structure for feeding material to and for delivering material from said pockets through said openings.

8. In a can filling machine, stationary frame structure, an upper measuring element having a top surface rotatably engaging said structure and also having openings therein, a lower measuring element having a bottom surface rotatably engaging said structure and also having openings therein in alinement with said upper element openings, a removable intermediate element having openings therein of fixed size alinable with said upper and lower element openings to form measuring pockets, said intermediate element being replaceable by other intermediate elements having differently sized openings therein, and means associated with said frame structure for feeding material to and for delivering material from said pockets through said openings.

In testimony whereof, the signature of the inventor is affixed hereto.

OSWALD H. HANSEN.
